UNITED STATES PATENT OFFICE

EMANUEL M. EISFELD, OF ROCHESTER, NEW YORK, ASSIGNOR TO BRAEBURN OF ROCHESTER, INC., OF ROCHESTER, NEW YORK, A CORPORATION OF NEW YORK

DESIGN FOR A NECKTIE HOLDER

Application filed April 24, 1930. Serial No. 35,372. Term of patent 3½ years.

To all whom it may concern:

Be it known that I, EMANUEL M. EISFELD, a citizen of the United States, residing at Rochester, in the county of Monroe and State of New York, have invented a new, original, and ornamental Design for a Necktie Holder, of which the following is a specification, reference being had to the accompanying drawing, forming part thereof.

In the drawing:

Fig. 1 is a front view; and
Fig. 2 is an edge view of a necktie holder embodying my new design.

I claim:

The ornamental design for a necktie holder, as shown.

E. M. EISFELD.
